UNITED STATES PATENT OFFICE.

JASON C. STEARNS, OF WORCESTER, MASSACHUSETTS.

ELECTRICAL FITTING.

1,144,849.

Specification of Letters Patent. Patented June 29, 1915.

Application filed March 18, 1914. Serial No. 825,712.

To all whom it may concern:

Be it known that I, JASON C. STEARNS, a citizen of the United States, residing at Worcester, in the county of Worcester and State of Massachusetts, have invented a new and useful Electrical Fitting, of which the following is a specification.

This invention relates to an electrical fitting suitable for general use but particularly adapted for use as a lamp fitting and especially as a fitting for the tail lamp of an automobile.

The principal objects of the invention are to provide a fitting of this character in which the current can be turned on and off readily at the fitting so that certain recent laws can be complied with which require the tail lamps to be so arranged that they cannot be turned off and on from the seat of the machine; also to provide a convenient and practical construction for this purpose; to provide an arrangement whereby the turning of a knurled head or the like will accomplish this result and positively break the circuit or make it as may be desired; and to provide improvements in the means by which the parts are turned for the purpose of connecting the lamp with the circuit and disconnecting it therefrom.

Reference is to be had to the accompanying drawings in which,

Figure 1 is a side elevation of a two-wire tail lamp fitting constructed in accordance with this invention; Fig. 2 is a longitudinal, central sectional view of the same with interior parts in elevation; Fig. 3 is a similar sectional view on the center line of Fig. 2 showing the parts in separated position; Fig. 4 is a transverse sectional view on the line 4—4 of Fig. 2; Fig. 5 is a side elevation of a form of connector showing how a three-wire connection can be arranged in accordance with this invention; Fig. 6 is an end elevation of one of the members of said connection partly in section; and Fig. 7 is an end elevation of the other member.

This fitting is shown in the first four figures as comprising a main socket member A having sockets in its opposite ends in one of which fits a plug B and in the other the lamp C. The socket member A has an external cylindrical metallic bushing 10 provided with a pair of L-shaped slots 11 at one end for the pins 12 of the base of the lamp as is well understood in this art. At

the other end this bushing is provided with double L-slots 13 for the pins 14 of the plug B. The bushing 10 is also provided with a circumferential slot 15. Inside this bushing is a cylindrical insulating member 17 preferably of hard rubber. This is oscillatably mounted in the bushing and is provided with a screw 18 which, of course, is removable and the head projects through the circumferential slot. This is for the purpose of preventing the longitudinal motion of this loose insulating member and for limiting its rotary motion. This bushing is also provided with a pair of spring-pressed plungers 20 eccentrically located, and similar to those shown in my Letters-Patent on an electric connector, No. 1,096,138. Consequently, the details of these plungers will not be described in full herein. Each of these plungers is, of course, insulated from the other. At the other end the member 17 is provided with spring-pressed plungers 21 for engaging the two metallic contacts 22 on the end of the lamp bulb. It will be understood of course that when this lamp is in its fixed position with its pins 12 in the ends of the L-slots 11 the two plungers 21 have to be turned to one extreme position in order to turn the current on and come into contact with the two metallic contacts 22. When this hard rubber member is turned away from that position these two plungers will move out of contact with these contacts and disconnect the lamp from the circuit. The other member B of the connector is shown as in the form of a plug having two sockets 23 which are also eccentrically placed and constructed in the same way as the sockets described in my above mentioned application and coöperate with the spring plungers 20 in that end of the member A. It will be observed that this plug, in order to be inserted, must be turned to a certain position with respect to the plungers 20, that is, the pins 14 must enter the straight part of the double slot 13 and at this time the screw head 18 must be at or near the center of the circumferential slot 15. When pushed in against the pressure of the springs, the plug can be turned in either direction and it turned for example to the right, in the form shown, until the pins reach the limit of their motion in that direction, the hard rubber member 17 will be turned to such position that the spring plungers 21

on the other end come into contact with the contacts 22 on the lamp and the circuit is complete. If, however, the plug is turned to the opposite position, the spring plungers 5 21 in the other end will move entirely out of contact with the contacts 22 of the lamp. Thus the current can be turned on and off simply by turning this plug. It will be seen furthermore that the plug cannot be removed 10 without turning the parts back to central position, to which position they must be returned to enable the plug to be inserted again.

The plug B itself has to be provided with 15 a knurled portion for use in turning it and for that purpose the following construction is shown: The hard rubber or other insulating member 25 which extends through the metal cylindrical plug portion 26 and which 20 carries the electrical connections therein is provided with a depression 27 near the end thereof. On the end of this hard rubber portion fits a cap 28 having an inwardly extending projection 29 for engaging said depression and preventing the relative rotation of these two members. This cap is provided with an internal diameter suitable for enabling it to fit loosely on the enlarged portion of the hard rubber member and has an 25 inturned flange 31 at its inner end adapted to fit against a shoulder 32 on the rear end of said enlarged portion. This flange is provided with two opposite passages 33 for permitting the pins 14 to pass through so that 30 the collar can be placed in position and will not easily come off. The collar has a screw-thread 35 at its inner end fitting the internal screw-thread on the cap. The collar and cap are screwed together tightly so that the two 35 40 knurled surfaces 38 and 39 on the collar and cap, but usually the latter alone, will constitute a gripping surface by which the operator can turn this plug for the purpose of turning the current on or off or removing the plug. The advantage of this construction is that contrary to the form shown in the last three figures, there is no chance of unscrewing the cap when turning the parts in the bushing.

50 In the form shown in the last three figures, a three-wire connection is shown and some modifications are also illustrated, although they are not any more adapted for a three-wire connection than for a two or four-wire one. In this case a connection is shown which may be applied to the head lamp if desired but no lamp support is indicated. A metallic bushing 40 is shown which is located in fixed position and in which is 55 loosely arranged a hard rubber cylindrical member 41 provided with three spring-pressed terminals 42 extending into the end of the bushing so that it constitutes the socket member. These terminals are provided with ferrules 43 on their outer ends

for connection with the wires. The bushing is provided with a circumferential slot 44 and the hard rubber member with a spring-pressed shouldered head 45 entering said slot for the same purpose as the screw head 70 in the other form shown, but this is more easily applied as it simply is pressed back against the spring and the hard rubber member forced into the bushing. When once in place it will not be displaced except 75 by positively forcing it in against the spring. Each of the terminals is provided with a spring inside the hard rubber for forcing its end out into the socket. The plug member 50 is provided with three sockets 51 for 80 receiving the three contact terminals 42 in the bushing and is formed, as in the other case, of a metallic casing having opposite pins 52 for engaging in the L-shaped slots 53 in the socket member and provided with 85 an enlarged shoulder 54 at the opposite end. In this casing is a hard rubber member 55 which receives the sockets and which projects beyond the enlarged end and is of the same diameter as said end. A cap 56 fits on 90 the end of this hard rubber member and is provided with an inward projection 57 extending into a depression in the hard rubber member. A collar 59 having a knurled surface fits on this cap, but in this case the cap 95 has an external screw-thread. In operation the collar alone is grasped for the purpose of manipulating the parts. In both forms shown it will be seen that the parts can be connected and disconnected very readily by 100 turning the collar and cap and that they are always left in proper position for replacement of the plug when desired.

Although I have illustrated and described only two forms of the invention, I am aware 105 of the fact that it can be carried out in many other forms and applied to the connection of other electrical devices and to other than two and three-wire systems without departing from the scope of the invention as expressed in the claims. Therefore, I do not 110 wish to be limited in these respects, but

What I do claim is:—

1. In a connector, the combination of a bushing, an insulating member adapted to turn therein on its own axis and having electrical terminals on each end thereof, means at one end of the bushing for holding a lamp or the like in one position so as to engage the terminals at one end of the insulating member when the insulating member is in one position and to be disconnected therefrom when in another position, means adapted to be inserted in the other end of said bushing for making an electrical connection with the terminals of that end of the insulating member and for positively controlling and turning said insulating member to connect and disconnect the terminals of the first named end with the lamp or the like, said bushing 120

125

130

135

having means for holding the last named means in either on or off position in the bushing.

2. In an electrical connector, the combination of a plug having electrical connections extending therethrough and provided with an end adapted to fit in a bushing, with a shoulder at the other end, a cap removably mounted on the end of the plug beyond said shoulder and incapable of turning thereon, and a collar on the plug engaging said shoul-

der and having a threaded connection with said cap, said cap thus constituting means for turning the plug.

In testimony whereof I have hereunto set my hand, in the presence of two subscribing witnesses.

JASON C. STEARNS.
